UNITED STATES PATENT OFFICE.

WENDEL JANOSIK, OF MAYNARD, OHIO.

DESIGN FOR A COMBINED SPOON, FORK, AND KNIFE.

53,165.

Specification for Design.

Patented Apr. 1, 1919.

Application filed January 23, 1919. Serial No. 272,775. Term of patent 7 years.

To all whom it may concern:

Be it known that I, WENDEL JANOSIK, a citizen of Czecho-Slovakia, residing at Maynard, in the county of Belmont and State of Ohio, have invented a new, original, and ornamental Design for a Combined Spoon, Fork, and Knife, of which the following is a specification, reference being had to the accompanying drawing, forming part thereof.

The figure is a view in perspective of the combined spoon, fork, and knife, showing my new design.

I claim:—

The ornamental design for a combined spoon, fork, and knife, as shown.

WENDEL JANOSIK.
